UNITED STATES PATENT OFFICE.

GEORGE H. EMERSON AND OLIVER C. CROMWELL, OF BALTIMORE, MARYLAND.

WATER-TUBE FIRE BOX FOR LOCOMOTIVE BOILERS.

Application filed December 1, 1925. Serial No. 72,567.

Our invention relates to boilers, and has special reference to locomotive boilers of the combined water-tube and fire-tube type, and in which a water-tube steam generator is formed in and as a component part of the locomotive firebox. These generators are generally constructed with top and bottom horizontal drums connected by vertical water-tubes beaded or otherwise fastened at their ends in the drums. Boilers of this type provide for the more economical use of steam, and make it possible, through increased heating surface and greater resistance to internal pressures, to generate and carry with safety a higher working pressure. They are also of advantage in that their construction facilitates the circulation of water which materially contributes towards the generation of steam. In all boilers of this type as previously constructed, however, the tubes have been so attached to the drums that they could not be cleaned or repaired without the necessity of the workmen entering the drums to perform this work. This has been a drawback and practical objection for reasons well known to those versed in the art which has militated against the more extensive use of such boilers as locomotive steam generators.

One object of our invention is to provide a construction which greatly facilitates assemblage and repairs, which permits the tubes to be reached and repaired and cleaned or turbined from the outside and without the necessity of the workmen entering the boiler, and which enables these operations to be performed in less time and at less labor cost.

Another object of our invention is to provide a novel construction and arrangement of parts for carrying the foregoing and other objects, hereinafter stated, into practical effect, and whereby a superior boiler structure is produced.

In the accompanying drawings illustrating the invention,—

Figure 1 is a diagrammatic cross-sectional view showing the general arrangement of the drums and water-tubes within the fire-box.

Figure 2 is a transverse section on an enlarged scale through one-half of the fire-box, showing more clearly the construction.

Figure 3 is a vertical longitudinal section through the fire-box and a portion of the barrel.

Figure 4 is an enlarged detail longitudinal section through one end of one of the drums and its connection with a water-leg.

Referring now more particularly to the drawings, 1 designates (generally) the firebox, 2 the barrel, 3 the front water-leg, 4 the rear water-leg, 5 the fire-tubes or flues, and 6 the grate line (the grate being omitted for clearness of illustration), of a boiler constructed in accordance with our invention. The front water-leg, which has a depending trough or well portion 7, comprises a front (outer) sheet 8 and a back (inner) sheet 9, said sheets having lapped flanges 10 riveted or welded together. The sheet 8 has an opening therein corresponding in diameter to the inner end of the barrel and is provided with a flange 11 extending from the wall of this opening and receiving such end of the barrel, which is riveted or welded thereto. The fire-tubes 5 are beaded or otherwise secured in openings in the sheet 9 and extend therefrom through the water-leg into the barrel. The rear water-leg 4 comprises a front (inner) sheet 12 and a back (outer) sheet 13, said sheets having lapped flanges 14 riveted or welded together. Said sheets are also provided with flanged portions 15 suitably united to form the fuel opening 16. The sheets comprising the water-legs are also suitably constructed to support the drums and to provide manholes for access thereto, as hereinafter fully described. The structural formation of the parts thus far described is preferred, although any other suitable structural formation may be employed.

Arranged within the top of the firebox are two similar side drums 17 and a single central drum 18, and arranged within the bottom of the firebox are two similar drums 19. All of these drums extend horizontally and longitudinally between the water-legs 3 and 4, and communicate therewith, and said drums, the grate and the cooperating parts of the steam generator are enclosed within the firebox casing formed by the water-legs and the boiler shell 20. As shown, the opposite ends of the drums, which are open, fit within annular flanges 21 projected from the walls of openings in the sheets 9 and 12, through which openings the ends of the drums communicate with the water-legs, the ends of the drums being riveted or welded to said flanges. The sheet 8 is also provided with manholes 22 communicating with the trough 7 in line with the front ends of the lower drums, while the sheet 13 is provided with similar manholes 23 in line with the rear ends of all the drums, said manholes being nor-

normally closed by detachable steam-tight closures 24, on removal of which access to the drums for inspection or cleaning may be obtained.

6 The upper side drums 17 are not connected with the other drums but communicate simply with the water-legs and are of fairly great diameter to form heating surfaces of large area. The central drum 18, however, 10 is connected with each lower drum 19 by two or more rows of vertical water-tubes, two rows of tubes, 25 and 26, respectively, being shown in the present instance. These tubes leading to and from both drums 19 are beaded 15 or otherwise suitably secured at their upper ends in holes 27 and 28 formed in the drum 18 and at their lower ends the tubes connected to each drum 19 are beaded or otherwise secured in holes 29 and 30 formed in said lower 20 drum. Although in practice the arrangement of these tubes may vary, it will be seen that in the illustrated disclosure the tubes 25 of each outer row extend vertically upward from the lower drum 19 and are bent 25 about the outer side and over the upper side of the overlying drum 17 and thence extend inwardly and horizontally to the adjacent side of the drum 18, while the companion tubes 26 of each inner row extend upward 30 from the lower drum 19 past the inner side of the overlying drum 17 and connect at their upper ends with the bottom of the drum 18. Thus the upper ends of the correspondingly arranged or laterally alined tubes 25 leading 35 from the lower drums 19 open horizontally into the drum 18 at opposite sides thereof in axial alinement with each other, while the upper ends of the correspondingly arranged, or laterally alined, tubes 26 leading from the 40 lower drums 19 open vertically into the bottom of the drum 18 close to and on opposite sides of its vertical center line. Formed in the top of the drum 18 in the vertical transverse plane of each group of holes 27 and 28 45 is an opening 31 closed by a detachable steam-tight cover 32, the openings 31 and covers 32 being equal in number to such groups of holes 27 and 28 and being exposed to the exterior at the top of the boiler, so that upon 50 the removal of any certain cover access to the interior from the outside may be obtained and the tube ends of the associated group of tubes exposed. The holes 29 and 30 formed in each lower drum 19 and receiving the 55 lower ends of the associated pair of tubes 25 and 26 of such a group are conveniently placed in transverse alinement at the top of the drum 19 and on its inner side in its quarter circumference between its vertical and 60 transverse centers, while the corresponding lower half of the outer side of said drum, diametrically opposite said holes, is provided with an opening 33 normally closed by a detachable steam-tight cover 34. These openings and their detachable covers are equal 65 in number to the transverse pairs of openings 29 and 30, and are exposed to the exterior at the base of the adjacent side of the boiler, so that upon the removal of any certain cover 70 34 the tube ends in alinement with the un-covered opening 33 will be exposed for inspection, cleaning or repairs. It will also be apparent from the foregoing that upon the removal of any certain cover 32 of the drum 18 and companion cover 34 of either 75 drum 19, the tube elements of any group extending between the two drums in question will be exposed for a convenient cleaning action, as by means of a turbine cleaner or other suitable flexible cleaning tool. The 80 tubes 25 of the outer row can be very conveniently bored and cleaned by entering the turbine through the drum 19 at an oblique or diagonal angle and extending it clear through to the drum 18. The tubes 26 of the 85 inner row may be turbined in a similar manner in either direction, i. e., by introducing the tool upwardly via drum 19 or downwardly via drum 18 as the entrance drum. The openings 33 give convenient access to 90 the lower ends of the tubes 25 and 26 for repair purposes. The openings 31 give convenient access to the upper ends of the tubes 25 for repair purposes, the upper ends of the tubes 26 being easily reached and the ends 95 of the tubes 25 being quite accessible. For greater convenience in repairing the upper ends of tubes 25, however, special tools suited to their 90° angle arrangement to the 100 openings 31 may be used. The construction 100 described not only facilitates assemblage of the tubes in the boiler, but saves time and labor in making inspection, repairs or replacements of tubes, thus overcoming a material objection hitherto present in boilers of 105 this type.

In practice the rows of tubes 25 and 26 may be set any desired distance apart at 110 points between their ends and the tubes of each row may be spaced as required with relation to each other, according to conditions in any particular boiler organization, to provide for their proper exposure to the flames and gases of combustion in order to secure maximum heating efficiency. Also in 115 practice the firebox shell or jacket 20 may be provided with any suitable type of heat insulating lining adapted to confine the heat within the firebox to an efficient degree. A preferred construction of insulating lining is 120 shown, the same comprising internal layer courses 35 of fire-brick or other similar material at the side and top of the firebox, the lower courses resting on the drums 19 as supports and the top courses being supported 125 from the upper drums by brackets 36 and bolts 37. These courses may be covered by an outside layer of non-conducting material 38 disposed between the lining and the shell or jacket 20. The jacket 20 may be of sectional 130

- construction, such as plates secured to the drums 19 by bolts 39 and at other points by the same bolts 37 which secure the fire-brick courses in place. The drum 18 may be and 5 preferably is enclosed wholly in the firebox, and the jacket and lining, therefore, are provided with a suitable longitudinal slot or opening 40 above the row of covers 32 to permit of access thereto, said opening 40 being 10 normally closed by detachable cover plates 41. These plates 41 may be fastened in position by the nuts applied to the same bolts 39 which hold the edges of the adjacent jacket plates or sections in place. 15 From the foregoing description, taken in connection with the drawings, the construction, mode of use and advantages of our invention will be readily understood by those versed in the art without a further and extended description. While the construction shown is preferred, it is obvious that many changes in the form, arrangement and construction of parts are possible, and we therefore do not desire to be limited to the particular embodiment disclosed, but reserve the right to make such changes and modifications as clearly fall within the spirit and scope of the invention as set forth in the appended claims. 25 Having thus fully described our invention, we claim:—
1. In a boiler, a pair of drums arranged one above the other, inner and outer rows of water tubes extending vertically between said drums, the tubes of said inner and outer rows respectively having their upper ends fitted in holes in a side and in the bottom of the upper drum, and the tubes of both rows having their lower ends fitted in holes in the 30 top of the lower drum at the inner side of its vertical center line, said upper drum being provided in its top with an opening lying in its central vertical plane and said lower drum being provided in its bottom with an opening on the outer side of its vertical center, said openings permitting access to the tube ends fitted in the drums, and a detachable closure for the opening in each drum. 35
2. In a water-tube firebox boiler, an upper drum at the top of the firebox having an opening at its top exteriorly exposed through the firebox shell and having tube receiving holes in its bottom and outer side, a lower drum at the bottom and one side of the firebox 40 having an opening in its bottom on the outer side of its center exposed exteriorly at the adjacent side of the firebox and having tube receiving holes in its top on the inner side of its vertical center at different distances therefrom, tubes having their lower ends respectively fitted in the outer and inner holes in the lower drum and having their upper ends respectively fitted in the side and bottom holes in the upper drum, and a closure for the 45 opening in each drum. 50
3. In a water-tube fire-box boiler, an upper drum at the top of the firebox, a pair of lower drums respectively located at each side of the firebox, said upper drum being provided in its bottom and opposite sides with rows of 70 tube receiving holes arranged in transverse groups and having at its top a row of openings, one for each transverse group of holes, exposed to the exterior at the top of the firebox, and each lower drum being provided in 75 its top with rows of transversely alined tube receiving holes located on the inner side of its vertical center and at different distances therefrom and having in its bottom a row of openings, one for each transversely alined 80 set of holes, located on the outer side of its transverse center and exposed to the exterior at the adjacent side of the firebox, detachable closures for the openings in the drums, outer rows of vertical tubes engaging the outer 85 rows of holes in the lower drums and the rows of holes in the opposite sides of the upper drum, and inner rows of vertical holes engaging the inner rows of holes in the lower drum and the bottom rows of holes in the upper drum. 90
4. In a boiler, the combination with a firebox shell, and front and rear water-legs, of side drums in the upper portion of the shell communicating solely with the water-legs, 95 a central drum in the upper portion of the shell communicating with the water-legs, side drums at the bottom of the shell communicating with the water-legs, and rows 100 of water-tubes connecting the central top drum with the bottom side drums, said drums being provided with means for permitting access to the tube ends fitted in the drums and to the interior of the tubes radially from the interior of the drums through the firebox shell. 105
5. In a boiler, the combination, with a firebox shell or casing, and front and rear water-legs, of upper side drums within the shell communicating solely with the water-legs, a central top drum within the shell communicating with the water-legs, bottom side drums within the shell communicating with the water-legs, an outer row of vertical 110 water-tubes extending from each bottom side drum upwardly to the central drum, said tubes having their upper portions disposed between the shell and adjacent upper side drum and bent inwardly over the latter and extending horizontally into the adjacent side of the central drum, and an inner row of 115 water-tubes extending from each lower side drum upwardly on the inner side of the overlying upper side drum, the inner rows of tubes from both lower side drums communicating at their upper ends with the central drum at the bottom thereof, the said central and lower side drums being provided with 120 openings for affording access to the tube ends and interior of the tubes radially 125 120
- 125

through said drums from the exterior of the firebox shell, and means for normally sealing said openings in said drums.

6. In a water-tube firebox boiler, upper 5 side drums, lower side drums, a central top drum, rows of inner and outer tubes leading from the lower side drums to the upper central drum and communicating with the latter respectively at the sides and at the 10 bottom thereof, the outer tubes being bent inwardly over the outer side drums and extending therefrom horizontally toward the central drum, said bottom side and central drums being provided with radial openings 15 for admitting access thereto, closures for said openings, a boiler shell through which said openings and closures are exposed, said shell including an outer jacket and an insulating lining therefor, and fastening means 20 carried by said drums and engaging said shell and lining and securing the same in position.

7. In a water-tube firebox boiler, the combination of a boiler shell comprising an outer jacket and an insulating lining therefor, of 25 lower side drums supporting the sides of said boiler shell and lining, a central top drum, said drums having radial openings, the radial openings of the bottom drums being exteriorly exposed below the sides of the shell 30 and the shell having an opening at its top exposing the opening in the top central drum, detachable closures for said openings in the drum, a detachable closure for the opening in the top of the shell, fastening means carried 35 by the drums for securing the elements of said shell in position, and water-tubes connecting the bottom drums with the top drum, the ends of said tubes and interior of the tubes being exposed through the drums on the removal 40 of the detachable closures.

8. In a boiler, the combination, with a firebox shell or casing having a clean-out opening at its top, and front and rear water legs, of a drum in the upper portion of the shell 45 communicating with the water legs and hav-

ing a clean-out opening in its top registering with said clean-out opening in the top of the firebox shell, bottom side drums within the shell communicating with the water legs, an outer row of vertical water tubes extending 50 from each bottom side drum upwardly to the said upper drum and having their upper ends extending horizontally into the sides of the upper drum, and an inner row of water tubes extending from each lower side drum 55 upwardly and communicating at their upper ends with the upper drum at the bottom thereof, said lower side drums having portions projecting outwardly beneath the side walls of the firebox shell and provided with 60 clean-out openings, the said clean-out openings in the firebox shell and drums affording access to the tube ends and interior of the tubes connecting the top drum with each lower side drum radially through said drums 65 via either drum from the exterior of the firebox shell, and means for normally sealing said clean-out openings in the fire-box shell and drums.

9. In a water tube firebox boiler, a top 70 drum, lower side drums, rows of inner and outer tubes leading from the lower side drums to the top drum and communicating with the latter respectively at the sides and at the bottom thereof, said top drum and bottom 75 side drums being provided with radial openings for admitting access thereto and to said tubes without entrance to the drums, closures for said openings, a boiler casing through which said openings and closure are exposed, 80 said casing including an outer jacket and an insulating lining therefor, and fastening means carried by said drums and engaging said casing and lining and securing the same 85 in position.

In testimony whereof we affix our signatures.

GEORGE H. EMERSON.
OLIVER C. CROMWELL.
